ATTORNEY.

UNITED STATES PATENT OFFICE.

CHARLES A. GREEN AND HENRY F. SCHUH, OF CHICAGO, ILLINOIS, ASSIGNEES TO THE
C. F. PEASE COMPANY, OF CHICAGO, ILLINOIS, A CORPORATION OF ILLINOIS.

DRAWING INSTRUMENT.

1,411,491.

Specification of Letters Patent. Patented Apr. 4, 1922.

Application filed October 16, 1920. Serial No. 417,365.

To all whom it may concern:

Be it known that we, CHARLES A. GREEN and HENRY F. SCHUH, citizens of the United States, residing at Chicago, in the 5 county of Cook and State of Illinois, have invented certain new and useful Improvements in Drawing Instruments, of which the following is a specification.

This invention relates to drawing instruments, and it comprises a divider or compass having one leg provided with a slot, a member adapted to be inserted therein, a flattened pin arranged transversely of said slot, the inserted member being provided 15 with a transverse slot having an enlarged head adapted to receive said pin.

In the usual construction of drawing instruments, the needle bar, pen compass, or pencil holder bar is inserted in a socket in 20 the leg of the instrument, whereby the inserted member may be removed and replaced by another member when the instrument is to be used for a different purpose. The inserted member is further provided with a 25 slotted connection or joint, whereby the lower end may be arranged at substantially right angles to the paper or surface on which the instrument is being used.

In the present invention, we have provided 30 an improved drawing instrument wherein the end of the leg of the instrument is provided with a slot arranged longitudinally and adapted to receive the reduced inner end of the needle bar, pen compass or 35 pencil bar holder. The end of the inserted member is provided with a transverse slot adapted to receive a flattened pin fixed in the end of the leg and arranged transversely of the slot therein. The transverse slot in 40 the reduced end of the inserted member is preferably in the form of a bayonet slot, having an enlarged head to receive the pin, whereby the inserted member, when in normal position, may be arranged at an angle 45 to the leg to permit the working end of the instrument to be arranged at right angles to the paper or surface. To remove the inserted member from the leg, it is turned to a position at substantially right angles to 50 the leg of the instrument to arrange the smaller diameter of the screw transversely in the slot in the inserted member and permit the inserted member to be removed from the leg of the instrument.

55 In the accompanying drawings, we have

shown one embodiment of the invention. In this showing:

Figure 1 is a plan view of the instrument showing a needle bar attached to each leg,

Figure 2 is a side elevation thereof, 60

Figure 3 is a plan view of one of the needle bars,

Figure 4 is a side elevation thereof,

Figure 5 is a side elevation of the needle bar provided with a bayonet slot, 65

Figure 6 is a plan view thereof,

Figure 7 is a transverse sectional view of the instrument shown in Figures 1 and 2,

Figure 8 is a plan view of a lengthening bar, 70

Figure 9 is a side elevation thereof,

Figure 10 is a plan view of the compass pen, adapted to be employed in connection with the invention,

Figure 11 is a side elevation thereof, 75

Figure 12 is a plan view of the pencil holder bar,

Figure 13 is a side elevation thereof,

Figure 14 is a plan view of the pencil holder complete, and, 80

Figure 15 is a side elevation thereof.

Referring to Figures 1 to 7 of the drawings, the invention comprises a pair of legs 1 and 2. These legs are connected to a yoke 3, at one end, having a finger piece or handle 4.

The legs are secured to the yoke by means of a pin or screw 5, passing through openings in the yoke and in the ends of the legs. A nut 6 may be provided to retain them in position. The legs are mounted in 90

the yoke to permit adjustment thereof, whereby the distance between the legs may be varied as is usual in instruments of this character. The lower end of the leg 2 is provided with a slot 3' for the reception of 95

the end of a needle bar 4'. The needle bar 4' is shown in detail in Figures 3 and 4 of the drawings. As shown, it is provided with a reduced end 5', adapted to be arranged in

the slot and is provided with an opening 6' 100 for the reception of a screw 7, passing through openings in the leg and through the opening 6'. This member is attached permanently to the instrument. It, of course,

may be withdrawn if desired, by entirely removing the pin or screw 7, but its attachment is comparatively permanent, in that the screw must be entirely removed to remove the needle bar. In the actual use of

the invention, it is only necessary to pro- 105

55 In the accompanying drawings, we have

shown one embodiment of the invention. In this showing:

vide one detachable member as the instrument includes one needle pin whether employed as a pen or pencil compass or as a divider. As shown, a needle point 8 is arranged in the end of this member, and is retained therein by means of a pin 9, provided with a fastening nut 10.

The leg 1 is provided with a slot 11, similar to the slot 3, and is adapted to receive the detachable member of the instrument. When employed as a pair of dividers, the needle holder shown in Figures 5 and 6 is used. Referring to these figures of the drawings, the needle bar comprises a body portion 12 having a reduced end 13, adapted to be arranged in the slot 11. As shown, the member is provided with a transverse slot 14 having an enlarged head 15. When the needle bar is arranged in position, a pin 16 is arranged in openings at each side of the slot and passed through the head 15 of the slot. As shown, the pin is provided with flattened portions 17 arranged opposite each other. The larger diameter of the pin is substantially the same as the diameter of the head of the slot 15. The pin is arranged in the fixed position shown in Figure 7 of the drawings. To remove the detachable member, the member is turned 90 degrees, whereby the reduced width of the pin is arranged transversely of the slot and the pin is capable of moving through the body portion of the slot. The pin is provided with a nut 18 (see Figure 2), whereby it is retained in adjusted position. To remove the detachable needle bar, the nut 18 is loosened and the member 12 turned at right angles to the position shown in Figure 7 of the drawings. The needle bar may then be removed from the side of the instrument, the pin passing through the slot 14. The detachable needle bar is provided with a needle point 19, retained therein in the usual manner, as by threaded pin 20 and nut 21.

In Figures 8 and 9 of the drawings, we have shown a lengthening bar 22, provided with a reduced end 23, adapted to be received in the slot of the leg in the manner just described. This reduced portion is provided with a transverse slot 24, having an enlarged head 25. The opposite end of the lengthening bar is provided with a longitudinal slot 26 similar to the slot 11 for the reception of a detachable needle bar or a detachable pen compass or pencil holder to be described. As shown, it is provided with openings 27 and 28, arranged on each side of the slot adapted to receive the flattened pin 16.

The pen compass employed in connection with our invention is shown in Figures 10 and 11 of the drawings. As shown, it comprises a body portion 29 of the usual construction having a reduced end 30, adapted to be arranged in the slot of the leg or the

slot of the lengthening bar. The reduced portion is provided with a transverse slot 31 having an enlarged head 32.

Referring to Figures 12 to 15 of the drawings, the pencil holder employed in connection with the invention comprises a body portion 33, having a reduced end 34. A slot 35 having an enlarged head 36 is arranged in the reduced end of the pencil holder. The pencil holder bar is provided with a socket 37, at its opposite end, for the reception of the pencil member 38, and adapted to receive a piece of lead, the lead being held therein by a threaded member 39.

The operation of the invention will be readily understood from the foregoing description. When the instrument is to be changed from a divider to a pen or pencil compass, or from a pen or pencil compass to a divider, the nut 18 is loosened and the member 12 turned at right angles. The detachable member then may be readily removed and another substituted. If a lengthening bar is to be used, it is secured to the end of the leg and the detachable member arranged in the other end of the lengthening bar. It will be apparent that the instrument will permit ready change of the detachable members as the pin does not have to be entirely removed to remove the detachable member.

It will be apparent that the present construction not only provides means for replacing one inserted member with another, but that it further provides means whereby the working end of the instrument may be arranged at right angles to the paper. By loosening nut 18, the needle bar, pen compass or pencil bar holder may be turned at an angle to the leg 1 and the nut then tightened, the needle bar, pen compass, or pencil bar holder being held in adjusted position by friction between the reduced end 5' and the sides of the slot in the leg.

It is to be understood that the form of our invention herewith shown and described is to be taken as a preferred example of the same, and that various changes in the shape, size, and arrangement of parts may be resorted to without departing from the spirit of the invention or the scope of the subjoined claims.

Having thus described our invention, we claim:

1. An instrument of the character described, comprising a pair of pivoted legs, a needle bar mounted in the end of one of said legs, the end of the other leg being slotted longitudinally, a detachable member arranged in said slot, said member being provided with a transverse slot extending from one side substantially to the center, and fastening means carried by said leg and adapted to enter said transverse slot.

2. An instrument of the character de-

scribed, comprising a pair of pivoted legs, a needle bar mounted in the end of one of said legs, the end of the other leg being slotted longitudinally, a detachable member 5 having a reduced end, the reduced end thereof being provided with a transverse slot extending from one side substantially to the center and being adapted to be arranged in the slot in the end of said leg, 10 and fastening means carried by said leg and entering said transverse slot.

3. An instrument of the character described, comprising a pair of pivoted legs, a needle bar mounted in the end of one 15 of said legs, the end of the other leg being slotted longitudinally, a detachable member arranged in said slot, said member being provided with a transverse slot having an enlarged head, and fastening means car- 20 ried by said leg and adapted to enter the head of the slot when the detachable member is assembled, said fastening member being adapted to be arranged in one position to permit removal of the detachable member.

4. An instrument of the character de- 25 scribed, comprising a pair of pivoted legs, a needle bar mounted in the end of one of said legs, the end of the other leg being slotted longitudinally, a detachable member having a reduced end adapted to be ar- 30 ranged in said slot, said reduced end being provided with a transverse slot having an enlarged head, and a pin carried by said leg and adapted to enter said transverse slot, said pin being flattened on opposite 35 sides to permit it to pass through the reduced portion of the slot, and being adapted to be turned at right angles when it is positioned in the enlarged head of said trans- 40 verse slot to prevent the removal of the detachable member.

In testimony whereof we affix our signatures in presence of two witnesses.

CHARLES A. GREEN.
HENRY F. SCHUH.
